BALL AND SOCKET SUPPORT FOR WORK HOLDERS

John W. Slavik, Warren, Ohio

Application January 9, 1952, Serial No. 265,701

2 Claims. (Cl. 248—181)

1

My invention relates to a support, more particularly to a support for a vise and the like, and the principal object of my invention is to provide new and improved supports of the class described.

In the arts which require use of a vise and the like, a great need has existed for a support which would enable the vise to be positioned in other than its normal horizontal position so as to hold the work most advantageously. Attempts have been made in the past to provide such a support but these attempts have been largely unsuccessful except for relatively light work such as model making. Prior art devices have been completely unsuccessful in providing a support with sufficient rigidity to enable its use with large vises and heavy work.

My invention provides a support for a vise and the like of great flexibility which permits the vise to be easily positioned and securely locked in such position even though holding relatively heavy work. The support lends itself well to mass-production economies and is reliable in use. These and other advantages will become apparent from a study of the detailed description which follows.

In the drawings accompanying this specification and forming a part of this application there is shown, for purpose of illustration, an embodiment which my invention may assume, and in these drawings:

Figure 1 is a side elevational view of a preferred form of my invention illustrating its use in supporting a conventional vise in horizontal position;

Figure 2 is an end elevational view of the embodiment illustrated in Figure 1, another position of the vise being shown in dot-dash lines;

Figure 3 is a view similar to Figure 1 but showing the support of my invention in longitudinal section, the vise supported thereby being shown in one position by full lines and in another position by dot-dash lines; and

Figure 4 is a fragmentary sectional view generally corresponding to the line 4—4 of Figure 3.

As illustrated in the drawings, my invention comprises a support indicated generally at 10 and having an outwardly extending arm 11 to which may be secured a conventional vise 12. It is to be understood that devices other than a vise could be secured to the arm 11, and as examples a table or a machine tool or the like could easily be secured to the arm 11 in place of the vise 12.

2

Referring particularly to Figure 3, the support 10 is presently shown to comprise a tubular member 13 having both ends open. The opening 14 on the left (as viewed in Figure 3) is adapted to provide an annular seat for a ball 15, and the opening on the right is adapted to be covered by an end cover plate 16. As illustrated in the drawings, the arm 11 is secured to the ball 15 and is adapted to extend laterally therefrom, the arm 11 presently being provided with a mounting plate 11a to which the vise 12 may be secured.

An annular member 17 is slideable in the bore 18 of the tubular member 13, and the member 17 has one end thereof formed to provide a generally semi-spherical opening 19 to receive the ball 15. This semi-spherical opening is presently lined with a relatively easily deformable material 20, such as lead, for a purpose to be shown.

A lever 21 is disposed within the member 13 and positioned transverse to the longitudinal axis thereof, opposed slots 22 in the member 13 preventing rotation of the lever and holding it in the transverse position shown. One end of the lever 21 bears against a fixed stud 23 secured in the end plate 16 and the other end of the lever, in the present embodiment, bears against a screw 24 which is threaded through the plate 16. A hand-wheel 25 is secured to the screw 24 to provide means for rotating the screw. A ball 26 is interposed between the member 17 and the lever 21, a depression 27 in the member 17 providing a seat for the ball and preventing displacement thereof.

A set-screw 28, having a lock-nut 30, extends through the wall of the tubular member 13 and as best shown in Figure 3, the set-screw 28 is engageable with the sides of a slot 29 in the member 17. This set-screw performs the function of a key and prevents rotation of the member 17 with respect to the tubular member 13.

As shown in Figure 1, the means for securing the end cover plate 16 to the tubular member 13 may comprise bolts 16a which pass through apertures in the plate 16 and which are threadably engageable with the member 13.

In operation, and assuming that the support 10 has been secured to a bench or the like by means of bolts 31 which pass through apertures in feet 32 formed on the member 13, the vise may be moved to the desired position and then locked in such position by rotating the hand-wheel 25 so as to move the screw 24 to the left. It will be appreciated that only a few of the many possible positions of the vise have been illus-

trated in the drawings, and if the vise is provided with the usual swivel base, as suggested in the drawings, it may additionally be rotated about its base in the usual manner.

When the screw 24 is moved to the left as heretofore described, it will rotate the lever 21 about the stud 23 which serves as a fulcrum. The ball 26 will be moved to the left thus forcing the member 17 into engagement with the ball 15. Since a comparatively high coefficient of friction is developed between the ball 15 and the relatively easily deformable material 20, and since the pressure exerted by the screw 24 is multiplied by the action of the lever 21, the ball 15 may be securely locked against rotation with the application of very little rotative effort supplied to the hand-wheel 25.

To reposition the vise, the holding pressure on the ball 15 must first be slightly relaxed by turning the hand-wheel 25. Since the holding pressure remaining will be just sufficient to prevent shifting of the vise by gravity, the user may grasp the vise and quickly and easily move it to the desired position. The hand-wheel 25 may then be rotated in the direction to securely lock the ball against rotation and thereby prevent further shifting movement of the vise.

In view of the foregoing it will be apparent to those skilled in the art that I have accomplished at least the principal object of my invention and it will also be apparent to those skilled in the art that the embodiment herein described may be variously changed and modified, without departing from the spirit of the invention, and that the invention is capable of uses and has advantages not herein specifically described, hence it will be appreciated that the herein disclosed embodiment is illustrative only, and that my invention is not limited thereto.

I claim:

1. A work positioning device, comprising a spherical member having means for attaching a work holder thereto, a tubular body enclosing said spherical member, said body being partially closed at one end to provide an internal annular seat for and conforming to the surface of said spherical member, a socket member housed within said body and movable axially toward said spherical member for holding the latter against said seat, a cap for closing the opposite end of said tubular body, a fulcrum carried by said cap in offset relation with respect to the axis of said socket member, a lever member housed within and extending transversely of said body, said lever member having one end bearing against said fulcrum, a ball disposed axially of said socket member and inter-

posed between the latter and said lever member, and means engageable with the opposite end of said lever for rocking the latter on its fulcrum and to transmit pressure through said ball to said socket member to force the latter against said spherical member.

2. A work positioning device, comprising a spherical member having means for attaching a work holder thereto, a tubular body enclosing said spherical member, said body being partially closed at one end to provide an internal annular seat for and conforming to the surface of said spherical member, a socket member housed within said body and movable axially toward said spherical member for holding the latter against its seat, means in part carried by said socket member and in part carried by said body for holding said socket member against rotation about its axis and including a slot extending in the direction of axial movement of said socket member and a set screw having a portion slidably fitting in said slot, a cap for closing the opposite end of said tubular body, a fulcrum carried by said cap in offset relation with respect to the axis of said socket member, a lever member housed within and extending transversely of said body, opposite ends of said lever member being slidably received within diametrically opposed slots formed in the inner wall of said body to hold said lever member against rotation about the axis of said socket member, said lever member having one end bearing against said fulcrum, a ball disposed axially of said socket member and interposed between the latter and said socket member, and a screw member threaded through said cap and having an end engageable with the opposite end of said lever, whereby inward threading of said screw member applies pressure against said lever and rocks the latter on its fulcrum to transmit pressure through said ball to said socket member to force the latter against said spherical member.

JOHN W. SLAVIK.
